ROOM DEODORIZER OR THE LIKE

Worthen Paxton, Port Chester, N. Y., assignor to Airkem, Inc., New York, N. Y., a corporation of New York

Application May 28, 1954, Serial No. 30,741

Term of patent 14 years

(Cl. D16—2)

To all whom it may concern:

Be it known that I, Worthen Paxton, a citizen of the United States, residing at Port Chester, in the county of Westchester and State of New York, have invented a new, original, and ornamental Design for a Room Deodorizer or the like, of which the following is a specification, reference being had to the accompanying drawing, forming part thereof, in which:

Fig. 1 is a side elevational view of a room deodorizer or the like embodying my new design and showing the vapor outlets partially open;

Fig. 2 is a top plan view of the deodorizer shown in Fig. 1;

Fig. 3 is a sectional view substantially on the line 3—3 of Fig. 1 showing details of the design.

I claim:

The ornamental design for a room deodorizer or the like, as shown.
